RECEPTACLE

John Visser, Grand Rapids, Mich., assignor to
 Grand Rapids Metalcraft Corporation, Grand
 Rapids, Mich., a corporation of Michigan

Application July 13, 1934, Serial No. 734,938

2 Claims. (Cl. 206—19.5)

The instant invention relates to wall receptacles and more particularly to ash receivers especially adapted for use when installed within the interior of a motor vehicle to a wall surface thereof.

The primary objects of the invention are to provide an ash receiver of the character above indicated having a receptacle detachably connected to a wall plate which is adapted to be secured to a wall surface of the interior of a motor car; to provide such a device whose several parts are detachably secured together in a novel manner, and, to provide such a device which is attractive in appearance, utilitarian in use, economical in manufacture and which may be readily and conveniently installed.

An illustrative embodiment of the invention is shown in the accompanying drawing, wherein:

Figure 1 is a front elevational view of the wall receptacle, the wall surface of the interior of a motor car being fragmentary and illustrative of the dash panel or interior upholstered wall;

Figure 2 is a sectional view thereof on line 2—2 of Figure 1;

Figure 3 is a plan view of the back plate of the wall receptacle showing the manner in which it may be secured to the wall surface of the interior of the motor vehicle and further showing in section a fragmentary portion of the receptacle per se and the manner in which it is detachably secured to its wall plate;

Figure 4 is a sectional view thereof on line 4—4 of Figure 3; and

Figure 5 is a sectional view on line 5—5 of Figure 3.

Referring to the drawing in which like parts of the device there shown are designated by the same numerals in the several views, a wall surface 10, such as the dash panel or interior upholstered surface of the interior of a motor vehicle, has secured thereto a wall plate 11 as by screws 12 passing through the screw receiving apertures 13.

This wall plate may be conveniently stamped from sheet metal if desired and has a circular marginal edge which is provided with a pair of oppositely disposed raised portions 14 and with a pair of oppositely disposed forwardly flanged portions 15. The raised portions are each likewise preferably provided with a boss 16 as best shown in Figure 3.

A receptacle generally designated 17 and likewise preferably formed of stamped and drawn sheet metal is here shown as outwardly bulging and at its top is provided with an ash receiving

opening 18. This receptacle is provided with a back plate 19, here shown as circular and preferably likewise formed of stamped sheet metal.

The circular marginal edge of this back plate is provided with a pair of projecting oppositely disposed and inwardly flanged tongues 20, the tongues each preferably having a boss 21 respectively adapted to register with the bosses 16 on the raised portions 14 of the wall plate 11 and to be engaged by them during the juxtaposition rotation of the container back plate 19 upon the wall plate 11 as indicated by the double headed arrow in Figure 1. The back plate 19 of the receptacle 17 when the receptacle is thus detachably secured to the wall plate 11, contacts the forwardly flanged portions 15 of the wall plate for spacing it from the wall surface 10 to which the wall plate is fixed, as best shown in Figure 2.

The wall surface, whether it be the instrument panel or the upholstered interior of the car, is thus prevented from becoming marred or otherwise defaced. A cigar or cigarette snuffer 22 is here shown as secured to the inner side of the back plate 19 and below the ash receiving opening 18.

It will thus be seen that the ash receiver herein shown and described may be readily and conveniently installed and when installed is attractive in appearance, utilitarian in use, economical in manufacture and is detachably secured in its assembled relation in a novel manner.

While but one specific embodiment of this invention has been herein shown and described, it will be understood that numerous details of the construction shown may be altered or omitted without departing from the spirit of this invention as defined by the following claims.

I claim:

1. In a device of the class described, a wall plate adapted to be fixed to a wall surface and having a circular marginal edge provided with a pair of oppositely disposed raised portions and with a pair of oppositely disposed forwardly flanged portions, and a container having a back plate provided with a pair of projecting oppositely disposed and inwardly flanged tongues adapted to engage the raised portions of the wall plate during the juxtaposition rotation of the container back plate upon the wall plate, said back plate contacting the forwardly flanged portions of the wall plate for spacing it from the surface to which the wall plate may be fixed.

2. In a device of the class described, a wall plate adapted to be fixed to a wall surface and having a circular marginal edge provided with

5 a pair of oppositely disposed raised portions and with a pair of oppositely disposed forwardly flanged portions, each of said raised portions having a boss thereon, and a container having a back plate provided with a pair of projecting oppositely disposed and inwardly flanged tongues, each of said tongues having a boss thereon respectively adapted to register with the bosses

on the raised portions of the wall plate and to be engaged by them during the juxtaposition rotation of the container back plate upon the wall plate, said back plate contacting the forwardly flanged portions of the wall plate for spacing it from the surface to which the wall plate may be fixed. 5

JOHN VISSER.
